UNITED STATES PATENT OFFICE.

JOHN M. HONAN, OF CHICAGO, ILLINOIS.

DESIGN FOR A WALL-COVERING.

SPECIFICATION forming part of Design No. 27,194, dated June 8, 1897.

Application filed April 19, 1897. Serial No. 632,872. Term of patent 7 years.

To all whom it may concern:

Be it known that I, JOHN M. HONAN, a citizen of the United States, residing at Chicago, in the county of Cook and State of Illinois, have invented and produced a new and original Design or Useful Shape for a Wall-Covering, of which the following, in connection with the accompanying drawings, is a full, clear, and exact specification.

In the said drawings, Figure 1 represents a plan or face view of a section of wall-covering embodying my design. Fig. 2 is a bottom view thereof and Fig. 3 is an enlarged transverse sectional view taken on the line 3-3, Fig. 1.

The leading feature of my design consists of a slab-like form substantially flat on one side and having its other side formed into a number of undulations, folds, depressions, and promontories A, which when viewed in plan, as in Fig. 1, present the appearance of

a bed of crumpled leaves projecting irregularly beyond the regular outline of the base portion B, as more clearly shown in Fig. 2, and which when viewed from the edge, as in Fig. 3, present the appearance of a series of puffs rising from the base B and being of more or less irregular contour.

Two diametrically opposite edges of the base B are formed with ribs or beads b, which, as shown in Fig. 3, are slightly embossed on the bottom of the base B.

Having thus described my invention, what I claim as new therein, and desire to secure by Letters Patent, is—

The new and original design or useful shape for wall-covering substantially as herein shown and described.

J. M. HONAN.
